UNITED STATES PATENT OFFICE.

GEORGE EDICK, OF ALBUQUERQUE, NEW MEXICO.

RAIL-JOINT.

1,109,407.

Specification of Letters Patent.

Patented Sept. 1, 1914.

Application filed June 8, 1914. Serial No. 843,845.

To all whom it may concern:

Be it known that I, GEORGE EDICK, a citizen of the United States, residing at Albuquerque, in the county of Bernalillo and State of New Mexico, have invented certain new and useful Improvements in Rail-Joints, of which the following is a specification.

This invention relates to new and useful improvements in rail joints, and has for its principal object to provide a rail joint in which the rails will be firmly held against accidental displacement.

Another object of the invention is to provide a rail joint in which the rail will be firmly held against creeping and sinking.

Still another object of the invention is to provide a novel means for holding the rail in place to prevent said rail from becoming loosened at the joint and causing the track to become weakened.

A still further object of the invention is to provide a novel means for locking the rails in the joint chair and maintaining them in their locked position until released by an instrument constructed for that purpose.

With these and other objects in view, the invention consists in the novel combination and arrangement of parts which will be fully set forth in the following specification, claims and drawings, in which:

Figure 1 is a longitudinal sectional view of a rail joint constructed in accordance with this invention, showing the locking mechanism in detail; Fig. 2 is a perspective view of the joint chair showing the details of construction; Fig. 3 is a transverse sectional view of the joint; Fig. 4 is a perspective view of one of the rail holding elements; Fig. 5 is a bottom plan view of a rail joint constructed in accordance with this invention; Fig. 6 is a longitudinal sectional view showing the detail construction of the rail locking members, and, Fig. 7 is a detail perspective view of the rail bond for use when electrical contact between rails is necessary.

Referring to the drawings by characters of reference, the numeral 1 designates as an entirety the rail chair which comprises the base plate 2, having formed at one of its lateral extremities the upstanding portion 3, which is bent back upon itself and the inner

edge thereof terminates in the web engaging member 4. A lateral extension 5 is formed at the edge of the base plate 2 opposite the upstanding portion 3, and is preferably of less thickness than the base plate. This extension 5 is provided near each end with the spaced apertures 6, the use of which will appear as the description proceeds. Intermediate the apertures 6 and spaced from the center of the extension 5 are provided slots 7 which are arranged to receive the locking spring, as will be more fully herein-after described. Extending longitudinally of the web engaging portion and located substantially centrally of the longitudinal extremities is provided the groove 8 in which the bow 9 of the rail bond designated generally by the numeral 10 rests. The free ends of this bow are held as at 11 in the angular extensions 12, which are formed at the terminals of the body portion 13, as clearly illustrated in Fig. 7. Located above the groove 8 are provided a plurality of segmental depressions 14, in which the enlarged segmental head members 15 of the locking pins 16 rest. Formed integral with the head members 15 are provided the stems 17 which extend beyond the surface of the web engaging member 4 and into the apertures 18 formed in the rail.

Coöperating with the member 1 is provided the member 19 which comprises the web engaging portion 20 having formed at its lower extremity the flange engaging portion 21. This flange engaging portion 21 terminates at its free edge in the inwardly extending portion 22, which is arranged to lie against the shoulder formed at the point where the extension 5 joins the base plate 2. A longitudinally tapering lateral flange 23 is formed on the side of the flange engaging portion opposite the portion 22 and is arranged to form a wedge by means of which the rail is firmly held in place.

The longitudinal bar which coöperates with the members hereinbefore described is designated generally by the numeral 24, and comprises a body portion 25, having formed near each end at spaced intervals the depending members 26 which are provided at their free ends with the angular extensions 27, the use of which is apparent upon referring to Fig. 5.

Intermediate the ends of the bar are pro-

vided the spaced recesses 28 through which the free terminals of the locking spring, which will be more fully hereinafter described, extend, these recesses 28 communicating with each other by the longitudinally extending rabbeted portion 29, as will be clearly seen upon referring to Fig. 4.

The locking spring hereinbefore mentioned is designated generally by the numeral 30 and comprises a main body portion 31, having its free ends bent upwardly as at 32. These ends are each provided with the angular extensions 33, which engage the portion 23 between the teeth 34 and thus hold the member 19 against longitudinal movement.

A suitable instrument, designated generally by the numeral 35 is provided and is arranged to release the spring to permit the several elements forming the joint to be removed. This instrument 35 comprises the main body portion 36 having the lever 37 pivotally secured thereto, as at 38. The end of the lever opposite the handle portion is pivotally connected to the sliding hook member 39, which is bent downwardly at its free end, as at 40, and is arranged to slide longitudinally of the body portion 36. A rigid hook 41 is connected to the end of the body portion 36 opposite the sliding hook member, and is provided with the downward extension 42, which forms the hook to engage the angular extensions 33. A suitable upstanding portion 43 is formed integral with the body portion 36, and is provided with a suitable pin 44, with which the pawl 45 which is pivotally secured as at 46 to the lever 37 cooperates.

It will be apparent from the foregoing that in use the rails are drilled in the ordinary manner and placed in position in the chair designated generally by the numeral 1, so that the projections 17 enter the apertures in the web of the rail. The locking bar 24 is then placed in position on the chair 1 in such a way that the extensions 26 will project through the apertures 6 and the extensions 27 will lie beneath the portion 5 of the plate 2, as illustrated in Fig. 5. The coöperating rail holding member 19 is then slipped between the locking bar 24 and the shoulder formed where the plate 2 joins the extension 5 until the teeth carried by the extension 23 are engaged by the angular extensions 33 on the spring 31, at which time the spring releasing instrument which is designated generally by the numeral 35 is placed on the spring, as illustrated in Fig. 1 and the lever 37 thrown into dotted position so that the pawl 45 will engage the pin 44 and hold the spring in its released position, at which time the coöperating rail clamping element 19 may be forced into place, and owing to the wedge surface of the extension 23, it will be ap-

parent that the rail will be firmly clamped in place. The pawl 45 is then released from the pin 44 and the handle 37 permitted to again assume its normal position, which will allow the extensions 33 to enter the spaces between the teeth and thus firmly hold the whole together.

It is to be understood that the rails which are used in connection with this rail joint are preferably provided with grooves at the point where the head joins the web and said grooves extend throughout their entire length. It will thus be seen that the inner walls of the groove will coöperate with the beveled edges of the web engaging members 4 and 20 and thus firmly lock the rail in place. With this construction it will be evident that a self-locking rail joint is provided and any danger of the rail becoming accidentally displaced is thereby eliminated.

While in the foregoing there has been shown and described the preferred embodiment of this invention, it is to be understood that such changes may be made in the combination and arrangement of parts as will fall within the spirit and scope of the invention as defined in the appended claims.

What is claimed is:

1. A rail joint including a rail chair, a locking bar removably secured to the rail chair, rail flange and web engaging members carried by the rail chair, the locking member and web engaging members being disposed at opposite sides of the rail chair, a coöperating rail engaging member slidably longitudinally of the rail chair between the locking bar and the web engaging member, a tapered flange formed on the coöperating rail holding member, said tapered flange engaging the locking bar and adapted to force the rail holding member toward the web engaging portion, a plurality of teeth carried on the upper surface of the flange, and means carried by the rail chair to engage the teeth and hold the coöperating rail engaging member against longitudinal movement.

2. A rail joint including a rail chair, web and flange engaging members formed on the rail chair, means carried by the web engaging portion to hold railroad rails against longitudinal movement, a lateral extension formed on the rail chair, said lateral extension being provided with a plurality of spaced apertures, a locking bar carried by the apertured edge of the extension, hooks formed on the locking bar and extending through the apertures to hold the bar in place, a coöperating rail holding member, a tapered flange carried by the coöperating rail engaging member, said member being slidable longitudinally of the rail chair, the tapered flange engaging the lock-

ing bar, a plurality of teeth on the upper surface of the flange, and a spring extending through the lateral extension on the rail chair and being provided with angular 5 extensions to engage the teeth and hold the coöoperating rail holding member against longitudinal movement.

In testimony whereof I affix my signature in presence of two witnesses.

GEORGE EDICK.
